OIL AND GREASE INTERCEPTOR

Edward W. N. Boosey, Detroit, Mich.

Application December 1, 1943, Serial No. 512,676

6 Claims. (Cl. 182—9)

1

This invention relates to oil and grease interceptors such as are used, for example, in restaurant kitchens to prevent the flow to the sewer of oils and greases discharged with water from sinks and dish washing machines.

One object of the invention is the provision of an interceptor which embodies an improved vent for the air and gas space at the top of the interceptor's liquid receiving chamber, and which interceptor is so constructed as to enable the liquid in said chamber to be normally maintained at a high level, even though the interceptor's water outlet orifice is located at a low level.

A further object of the invention is the provision of an interceptor having an effective air lock between the air and gas space and the water outlet orifice, said air lock maintaining in said space a substantially constant volume of air and gas at a substantially constant head or pressure and preventing or minimizing surging effect of the incoming liquid, such as would otherwise normally occur on sudden inflow.

Still another object of the invention is the provision of an interceptor having structural simplicity, a relatively high capacity and improved operating efficiency.

Further objects of the invention are in part obvious and in part will appear more in detail hereinafter.

The invention will be readily understood, and many of its practical advantages will be referred to in, or will be evident from, the following description of the preferred structural form of such invention, as illustrated in the accompanying drawings, in which

Fig. 1 is a longitudinal sectional view of the preferred form of interceptor embodying the present invention, the view being on the line 1—1 of Fig. 2;

Fig. 2 is a transverse sectional view, on the line 2—2 of Fig. 1;

Fig. 3 is a fragmentary longitudinal sectional view, on the line 3—3 of Fig. 4, of still another form of interceptor embodying the present invention; and

Fig. 4 is a transverse sectional view on the line 4—4 of Fig. 3.

Before the interceptors here illustrated are specifically described, it is to be understood that the invention here involved is not limited to the details of construction or the arrangement of parts here shown, as the invention obviously may take other forms. It also is to be understood that the phraseology or terminology herein employed is for purposes of description and not of

2

limitation, the scope of the present invention being denoted by the appended claims.

In all of the forms thereof here shown, the interceptor embodies a closed tank or vessel of relatively large capacity and to which is admitted, through an inlet orifice in one of its side walls, the oil and/or grease-containing liquid discharged, for example, from a sink or a dish washing machine. Through said inlet orifice, the discharged liquid, and more or less air, flows to the main chamber of the interceptor, preferably by way of some means which retards liquid flow and assists in the stratification of the oil, grease and water, the oil and grease collecting on the top of the water for retention in said chamber. From this main chamber, and preferably from a low level therein, the water flows upwardly through the generally upright channel of an outlet conduit, from which it flows over the upper edge of a wall serving as a dam or weir into a discharge or spill-over chamber. Communicating with this chamber is the water outlet orifice of the interceptor, said orifice being located, at least in part, below the top edge of said dam or weir-forming wall and communicating with the sewer to which the water, now freed of its oil and grease, is to be delivered. The top edge of this wall (or the crest of the dam or weir, to put it another way) determines the normal liquid level in the main chamber and in the water outlet channel leading therefrom, so that the interceptor's water outlet orifice may be located at as low a level as desired. For the purpose of stabilizing operating conditions, the air and gas space at the top of the main chamber is vented to the generally upright water outlet channel, the vent preferably (but not necessarily) embodying or being associated with an air lock or liquid seal which normally prevents direct communication between said air and gas space and the spill-over chamber and hence between said air and gas space and the water outlet orifice. In any event, the parts establishing the air vent and the dam or weir-forming wall are so constructed and arranged as to prevent or minimize surging effect of the incoming liquid, such as would normally occur upon a sudden gush or inflow of liquid and air into the interceptor.

Referring now to the interceptor of Figs. 1 and 2, shown as made of metal but which may be made of any suitable material, it will be noted that such interceptor comprises a body 30 having a removable cover 31, the body and cover together enclosing the main chamber 32. To receive the liquid discharged by a sink or a dish

washing machine through the pipe 33, one of the side walls of the body 30 is provided with an inlet orifice 34, and through such orifice, the incoming liquid enters the generally upright channel 37 of a conduit 35, open at its bottom and at its top to the main chamber 32. The provision of this conduit, with its open ended channel 37, retards the velocity of the incoming liquid and initiates stratification of the oil, grease and water. To assist in effecting such stratification, the wall portion 36 of the conduit, opposite the inlet orifice 34, may be inwardly and upwardly inclined, as here shown.

The wall portion 36 due to its inclined relationship tends to retard the velocity of flow of liquid thereto whereby time is afforded for the water to flow downwardly in the channel 37 of the conduit 35, to thereby enter the chamber 32 adjacent the bottom thereof. Similarly, the grease and oil, together with the incoming air, are caused to flow, to a greater or lesser extent, upwardly in the channel 37 and thus enter the upper portion of the chamber 32.

Adjacent a side wall of the body 30, there is a water outlet conduit 39 having an open lower end adjacent but spaced from the bottom wall of said body. After being freed of its grease and oil, the water enters the open lower end of this conduit and flows upwardly through the channel 38 provided thereby. To one side of the upper end portion of said water outlet conduit, there is a spill-over chamber 42, and the top edge 44 of a wall portion 43 between the channel of such conduit and said chamber serves as the dam or weir for determining the normal liquid level (indicated by the dot-dash line A—A in Fig. 2) in the main chamber 32 and in the channel 38 of the water outlet conduit 39. Communicating with the spill-over chamber 42 and located entirely below the normal liquid level A—A is the water outlet orifice 45, which communicates by a pipe 41 or the like with the sewer to which the water is to be discharged. The location of the bottom wall 40 of the spill-over chamber determines the depth of such chamber and hence the level to which the water outlet orifice 45 can be lowered. It is quite evident, however, that such outlet orifice can be located at a much lower level than that here shown if the spill-over chamber is given the necessary depth.

In this form of the invention, the top of the spill-over chamber 42 and the entire upper end of the water outlet channel 38 are covered by a closure member 46, releasably held in sealing position, in spaced relation to the top edge 44 of the dam or weir-forming wall portion 43, by the depending feet 31a of the body cover 30. Therefore, by simple removal of the bolts 47 which releasably hold the body cover in sealing position, the closure member 46 may be readily lifted from its seat upon the upper edges of the external side walls which form the spill-over chamber 42 and the upper end portion of the water outlet conduit 39.

For venting the air and gas space at the top of the main chamber 32, the closure member 46 has extended therethrough a tube 48, here shown as integral with said closure member. The open upper end of said tube is in communication with said air and gas space, and the open lower end of said tube is in communication with the water channel 38 of the outlet conduit 39. Inasmuch as the lower end of said tube is below the normal liquid level A—A, indicated in Fig. 2, the vent passageway provided by said tube is

normally sealed by the water in said channel.

If desired, and as here shown, the cover 31 of the interceptor of Figs. 1 and 2 may have a dome-shaped portion 31b which overlies the open upper end of the vent-forming tube 48, and for manufacturing simplicity and economy, the spill-over chamber 42 and the water outlet conduit 39 may be integral parts of a unitary structure detachably mounted within the main chamber 32 on the inwardly projecting end of the water discharge pipe 41 leading to the sewer. The operation of the interceptor of Figs. 1 and 2 will be evident from the foregoing description of its construction.

In Figs. 3 and 4, there is fragmentarily shown an interceptor which differs but slightly from the one shown in Figs. 1 and 2, and corresponding parts of these two interceptors are therefore designated by the same reference numerals. Primarily, the interceptor of Figs. 3 and 4 differs from the interceptor of Figs. 1 and 2 in that its spill-over chamber 42 is located above a part of the lower end portion of the upright channel 38 of the water outlet conduit 39, and in that the lower end of the vent tube 48 terminates above the normal liquid level, as determined by the top edge 44 of the wall 43 which separates the spill-over chamber 42 from the upper end portion of the water outlet channel 38. Notwithstanding the fact that the lower end of the vent tube 48 is above the normal liquid level, there is a control of liquid surge in this interceptor. This control occurs because of the rise of liquid level upon initial inflow of liquid to the interceptor, effecting a temporary submergence of the lower end of the vent tube 48 and thereby providing a temporary liquid seal which enables the air and gas in the space above the main chamber to "dampen" any tendency for excess surge. In this form of the invention, the closure member 46 for the spill-over chamber 42 and the water outlet channel 38 is bolted in place, as at 49, although if desired such closure member may be held in place by depending feet of the body cover 31, as in that form of the invention shown in Figs. 1 and 2.

It will be evident from the foregoing description and drawing that the various features and objects of the invention are attained by the structural arrangement and form of the several parts hereinbefore described. Having thus briefly described my invention, its utility and mode of operation, what I claim and desire to secure by Letters Patent of the United States is:

1. A grease interceptor, comprising a body having a removable cover providing an air-tight chamber and an inlet thereto, a conduit open to the lower portion of said body chamber and providing an upwardly extending liquid outlet channel, a closure for the upper end of said conduit and the channel thereof, a series of lugs on the cover engaging the closure to maintain the same in position, wall means providing a discharge chamber within the closed upper end portion of said outlet conduit, there being a discharge passageway from said outlet channel to said discharge chamber, said body being provided with a discharge orifice in communication with said discharge chamber, the bottom of said discharge orifice being located at a lower level than that of the bottom of said passageway at said outlet channel, the bottom of said passageway at said outlet channel thereby determining the normal liquid level in said body chamber and in said channel, and a vent conduit for an air and gas

space at the top of said body chamber, said vent conduit extending through said closure with its upper end in communication with said air and gas space, the lower end of said conduit extending down into said outlet channel and terminating below said discharge passageway, whereby said vent conduit is normally sealed from said discharge chamber by the liquid in said vent channel.

2. A grease interceptor, comprising a body providing an air-tight chamber, an inlet thereto, a conduit open to the lower portion of said body chamber and providing an upwardly extending liquid outlet channel therefrom, means including a cover providing an air-tight discharge chamber laterally of said outlet channel, there being a common wall portion between said discharge chamber and said outlet channel which terminates below the top of said chamber and above the top of said outlet channel, with the consequent establishment of communication between said chamber and said outlet channel over the upper edge of said wall portion, said body having an outlet orifice for said discharge chamber which communicates with said chamber below the upper edge of said wall portion, whereby said upper edge of said wall portion determines the normal liquid level in said body chamber and said outlet channel, said body chamber being provided with an air and gas space above the liquid therein, and means for venting said air and gas space to said discharge chamber, said vent means being closed by the liquid in said outlet channel when such liquid is at its normal level, said discharge chamber including a cover held in position by a series of lugs on the body cover.

3. A grease interceptor, comprising a body having a cover providing an airtight chamber and an inlet thereto, a conduit open to the lower portion of said body chamber and providing an upwardly extending liquid outlet channel therefrom, said conduit being open at its upper end, means providing a discharge chamber laterally of said outlet channel and open at its top, an air-tight closure for the top of said discharge chamber, a plurality of lugs on the cover engaging the closure to maintain the same in position said closure having a portion projecting over a portion of the open upper end of said outlet conduit, said body being provided with a discharge orifice in communication with said discharge chamber below the closure for said chamber, means providing a discharge passageway from said outlet channel to said discharge chamber, said passageway being located below said closure, the lowermost portion of said passageway at said outlet channel being located above the lowermost portion of said discharge orifice, whereby said passageway determines the normal liquid level in said body chamber and in said outlet channel, the uncovered upper end portion of said outlet conduit providing a vent for an air and gas space at the top of said body chamber, and means extending from the projecting portion of said closure downwardly into said outlet channel below the normal liquid level therein to thereby enable the liquid in said outlet channel to nor-

mally prevent communication between said vent and said passageway to the discharge chamber.

4. A grease interceptor, comprising a covered body having an air-tight chamber and an inlet thereto, a conduit open to the lower portion of said body chamber and providing an upwardly extending liquid outlet channel therefrom, means providing a discharge chamber laterally of said outlet channel, an air-tight closure for said discharge chamber, means carried by the cover of said body and engaging said closure for releasably holding said closure in place, there being a discharge passageway from said channel to said discharge chamber below said closure, said body having an outlet orifice for said discharge chamber, and means for venting said discharge chamber and air and gas space at the top of said body chamber, to the outlet conduit.

5. A grease interceptor, comprising a covered body providing an air-tight chamber and an inlet thereto, a conduit open to the lower portion of said body chamber and providing an upwardly extending liquid outlet channel therefor, means providing a discharge chamber laterally of said outlet channel, an air-tight closure for said discharge chamber, depending projections carried by the cover of said body and engaging said closure for releasably holding said closure in place, there being a discharge passageway from said channel to said discharge chamber below said closure, said body having an outlet orifice for said discharge chamber, and means for venting said discharge chamber and air and gas space at the top of said body chamber to the outlet channel.

6. A grease interceptor, comprising a chambered body having an inlet connection and an outlet connection, means within the body connected adjacent its upper end with the outlet connection and providing an outlet channel open at its lower end to the lower portion of the body chamber and providing also a discharge chamber laterally of said outlet conduit, a wall of the said discharge chamber lying between the outlet channel and the outlet connection and having its upper edge below the top of the discharge chamber and above the outlet connection, and a tube providing a channel opening at one end to an air space in the body chamber and at its opposite end terminating in the outlet channel at such a level with respect to the upper edge of said wall as will reduce surge in the body chamber.
